SHOE MACHINE

Bernhardt Jorgensen, Marblehead, Mass., assignor to United Shoe Machinery Corporation, Flemington, N. J., a corporation of New Jersey

Application May 4, 1944, Serial No. 534,052

26 Claims. (Cl. 12—14)

This invention relates to machines for operating on shoes, and more particularly to means for positioning and controlling shoes in such machines. The invention is herein illustrated as applied to a toe-end lasting machine constructed generally as disclosed in United States Letters Patent No. 2,324,509, granted on July 20, 1943, on an application of mine, but it is to be understood that it is not thus limited in its applicability.

It has been proposed heretofore to provide a machine such, for example, as that shown in the above-mentioned Letters Patent with a pair of projections or spurs within view of the operator for positioning shoes in the machine as determined by engagement with the insole of each shoe in a pair of holes previously provided in its forepart in locations spaced apart widthwise of the shoe. Such a disclosure is found in United States Letters Patent No. 2,291,630, granted on August 4, 1942, on an application of mine. In that manner the shoe is properly positioned bodily both lengthwise and laterally, and its position with respect to lateral swinging movement is also definitely predetermined. The present invention, in one aspect, provides for the accomplishment of the same result with respect to the positioning of the shoe by engaging the insole in a single hole therein and by the further use of side-gaging means. For the purpose in view, the construction herein shown comprises a single pointed projection or spur arranged to engage the insole in a hole located substantially midway between the opposite sides of its forepart to position the shoe bodily both lengthwise and laterally, and a pair of side gages arranged to engage the opposite sides of the toe-end portion of the shoe to determine its position with respect to lateral swinging movement about the axis of the hole in the insole. In the presentation of the shoe to the machine its toe-end is properly positioned by the side gages without any special care or attention on the operator's part, and all that he need do is insure that the projection or spur will properly enter the single hole in the insole. Not only is this more readily accomplished than if it were necessary to insure registration of two projections with corresponding holes in the insole, but the fact that there is only one hole located substantially equidistant from the opposite sides of the shoe insures that regardless of the size of the shoe the hole will be well away from the marginal portions of the upper materials which usually will have been lasted over the insole at the sides of the forepart beyond the toe

portion of the shoe. In the application of the invention to the machine shown in Letters Patent No. 2,324,509, which is provided with side grippers arranged to grip and pull the upper at the sides of the toe and adjustable toward and from each other for shoes of different sizes, the side gages, as herein illustrated, are arranged to be adjusted with the side grippers. The gages are, moreover, displaceable heightwise of the shoe after the positioning of the shoe by the movements of wipers with which the machine is further provided for wiping the margin of the toe end of the upper inwardly over the insole.

To assist in preventing lengthwise displacement of each shoe from the position determined as above described, the invention further provides a heel-end support of novel construction, including a heel rest arranged to engage the heel-end face of the shoe. In order to avoid danger of marking the upper by pressure unduly localized thereon, the heel rest herein shown is curved for engagement with the upper over a substantial area widthwise of the shoe, although confined to engagement with the heel-end face of the upper, its upper-engaging portion comprising a flexible band of leather or other suitable material. Since a heel rest so constructed would have a tendency to displace the heel end of a shoe laterally unless properly positioned widthwise of the shoe, and in view of the fact that in a machine such as that to which the invention is herein shown as applied the heel ends of right and left shoes occupy different positions widthwise of the machine, the construction shown is further such that the heel rest is mounted for movements in directions widthwise of the shoes and has associated with it means for engaging each shoe to position it in proper relation thereto. As herein illustrated, a pair of arms movable with the heel rest toward the shoe lengthwise thereof are arranged to centralize it widthwise of the shoe by engagement with the sides of the heel end of the shoe. In order to minimize the movement required thus properly to position the heel rest, it is controlled by a pair of oppositely acting springs which determine its initial position and through which it may be adjusted into approximately correct positions for right and left shoes respectively.

50 The above and other features of the invention, including various novel details of construction and combinations of parts, will now be more particularly described with reference to the accompanying drawings and thereafter pointed out in the claims.

In the drawings,

Fig. 1 is mainly a plan view of a portion of the machine shown in the previously mentioned Letters Patent No. 2,324,509 as modified for purposes of the present invention;

Fig. 2 is a view in right-hand side elevation of a portion of the structure shown in Fig. 1;

Fig. 3 is a view partly in front elevation and partly in section on the line III—III of Fig. 1, showing the shoe-positioning means in its relation to a shoe also shown in section;

Fig. 4 is a view similar to Fig. 3, illustrating how the side gages are displaced heightwise of the shoe by the wipers;

Fig. 5 is a view partly in left-hand side elevation and partly in section, further disclosing the construction of the shoe-positioning means and showing also the heel-end support for the shoe;

Fig. 6 is a plan view of the heel-end support in its operative relation to a shoe shown diagrammatically; and

Fig. 7 shows the forepart of a shoe prepared for presentation to the machine.

As fully disclosed in Letters Patent No. 2,324,509, the machine to which the invention is herein shown as applied is provided with a toe-end gripper 2 and with a pair of side grippers 4 for gripping the margin of the toe end of the upper and for pulling the upper respectively lengthwise and widthwise of the last, with a toe former 6 which embraces the upper about the toe end of the last and is moved upwardly to wipe the upper heightwise of the last, and with a pair of wipers 8 which are moved upwardly with the toe former opposite the end and the sides of the toe and are operated thereafter to wipe the margin of the upper inwardly over an insole a on the last. The shoe is positioned by means mounted on a slide 10 of skeleton form vertically adjustable along guideways on the frame of the machine, and its forepart is clamped against the shoe-positioning means by a toe rest 12 and an instep support 14 (Fig. 5) which are moved upwardly into clamping position substantially at the beginning of the power operation of the machine.

The toe-end gripper 2 comprises a pair of jaws one of which is moved toward the other to grip the margin of the upper by a piston 16 (Fig. 5) movable in a cylinder 18 to which operating fluid is admitted at the proper time. The cylinder 18 is fast on a slide 20 movable along guideways 22 (Fig. 1) on a gripper support 24 to cause the gripper to pull the upper lengthwise of the last. The means for thus operating the slide 20 need not be herein described. Similarly, each side gripper 4 comprises a pair of upper-gripping jaws one of which is moved toward the other to grip the upper by a piston 26 movable in a cylinder 28 by fluid admitted to the cylinder. A laterally extending flange portion of each cylinder 28 is secured by a screw 30 and a dowel pin 32 in fixed relation to a slide 34 movable in a direction at right angles to the direction of movement of the toe-end gripper along guideways 36 on the gripper support 24. Operative movement is imparted to the left-hand slide 34 to cause the corresponding side gripper 4 to pull the upper by a piston 38 movable in a cylinder 40 pivoted on a stud 41 on the gripper support 24, this piston being pivotally connected to one end of a lever 42 which is pivotally mounted between its opposite ends on a stud 44 on the support 24. Also pivotally mounted on this stud is one arm 46 of a three-armed lever 48 which

has a second arm 50 extending forwardly and connected at its front end to the slide 34. The left-hand end of the lever 42 is connected by a spring 52 to the front end portion of the arm 50, and this spring acts to hold the left-hand end of the lever 42 normally in engagement with a lug 54 on the three-armed lever 48. Accordingly outward movement of the piston 38 in the cylinder 40 serves to swing the lever 42 and the three-armed lever 48 as a unit about the stud 44 and thereby to operate the slide 34 to impart upper-pulling movement widthwise of the shoe to the left-hand side gripper. It will be understood that the spring 52 is yieldable in response to resistance of the upper to the force of the pull applied thereto to permit the lever 42 to swing relatively to the three-armed lever 48. A lug 56 on the support 24 serves as a stop to limit movement of the piston 38. The left-hand side gripper is returned to its initial position, when permitted, by a spring 58 connected to the lever 42 and the support 24.

The mechanism for imparting upper-pulling movement to the right-hand side gripper 4 is of substantially the same construction and operates in the same manner as that above described as associated with the left-hand side gripper, and corresponding parts are identified by the same reference characters. The lever 42 through which the right-hand gripper is operated is pivotally connected to a piston 60 movable in a cylinder 62 which is pivoted on a stud 64 on the support 24. Movement of the piston 60 is limited by engagement with a lug 66 on the support. As fully explained in Letters Patent No. 2,324,509, all the grippers are operated simultaneously to pull the upper by fluid admitted to the cylinders associated therewith.

The initial positions of the side grippers 4 with respect to movements widthwise of the shoe are adjustably determined, in the construction herein shown, by mechanism differing somewhat from that disclosed in the above-mentioned Letters Patent. Supported over the top of a cover plate 68 on the gripper support 24 is a lever 70 which has on its left-hand end a depending pin 72 arranged to engage a third arm 74 of the left-hand three-armed lever 48 to determine the initial position of the left-hand side gripper. The lever 70 is mounted to swing about a stud 76 on the cover plate 68, and a rounded portion on its right-hand end extends into a slot 78 in another lever 80 which is pivotally mounted on a stud 82 on a second cover plate 84 on the gripper support 24. The right-hand end of this lever carries a depending pin 86 (Fig. 2) arranged to engage the third arm 74 of the right-hand three-armed lever 48 to determine the initial position of the right-hand side gripper 4. To control both the connected levers 70 and 80 there is threaded in a lug 88 on the gripper support 24 a rod 90 the rear end of which is arranged to engage the pin 86. It will be evident that by such engagement the rod 90 determines the initial positions of both side grippers, the pin 86 being held against the end of the rod by the action of the springs 58 on the three-armed levers 48. Connected by a universal joint 92 to the rod 90 is a rod 94 which extends through the front of the frame and has on its front end a knob 96 for turning it to adjust the side grippers toward or from each other for shoes of different widths, the levers 70 and 80 being so constructed and arranged that the grippers receive equal movements toward or from each other as they are

thus adjusted. The pin 86 is in eccentric relation to a stem 98 extending therefrom and mounted to turn in the lever 80, the stem and pin being held in adjusted relation to the lever by a nut 100 threaded on the stem. It will, therefore, be evident that by turning the pin 86 the positions of the levers 70 and 80 may be altered to vary correspondingly the initial position of the left-hand side gripper without altering the position of the right-hand side gripper. By combined adjustments of the pin 86 and the rod 90, moreover, the initial position of the right-hand side gripper only may be varied.

For purposes of this invention, the means herein previously referred to as mounted on the slide 10 for positioning the shoe comprises a sole rest member 102 having a vertically flat portion extending lengthwise of the shoe and upwardly into a slot 104 (Fig. 1) in the slide 10. The member 102 is supported and is guided for adjustment about an axis extending widthwise of the shoe by two pins 106 which extend across the slot 104 through a curved slot 108 in the member. The portion of the member 102 which is located nearest the end of the toe is provided with laterally and downwardly extending wings 110 arranged to bear on the bottom face of the insole in locations spaced from each other widthwise of the shoe by a recess 112 (Fig. 5) in the lower face of the member. Similarly, the portion of the member which is farthest from the end of the toe is provided with laterally and downwardly extending wings 114 arranged to bear on the insole in locations spaced apart widthwise of the shoe by a recess 116 (Fig. 3) in the member. Bearing on the wings 114 are springs 118 mounted in sockets in the slide 10 and tending to tip the member 102 in one direction about the axis determined by the pins 106 and the slot 108. Threaded in the slide 10 is a screw 120 the end of which is arranged to bear on a face 122 (Fig. 5) of the member 102 to limit tipping movement of the member by the springs 118 and to adjust the member about its axis as may be necessary to position in proper relation to the wipers 8 the toe ends of shoes of different styles. It will be evident that by its engagement with the bottom face of the insole the member 102 serves to determine the position of the shoe heightwise and with respect to lengthwise or lateral tipping movements. To position the shoe bodily both lengthwise and laterally there is fast in that portion of the member 2 which is farthest from the toe end of the shoe a pin 124 having a lower conically pointed end extending through and beyond the recess 116 for engagement with the insole in a correspondingly formed hole b (Fig. 7) previously provided in the insole substantially midway between its opposite side edges in predetermined relation to the contour of the shoe. Such a hole may be formed in the insole by a machine such as disclosed in Letters Patent No. 2,291,631, granted on August 4, 1942, on an application of mine, but suitably modified to form a single hole instead of two holes. It will be noted that the hole thus formed, as herein illustrated, extends only part way through the insole, although the present invention is not limited in that respect. The lower end of the pin 124, located as above described, is within view of the operator when he presents a shoe to the machine, and he may, therefore, readily present the shoe in such manner that the pin enters the hole provided in the insole.

Further to determine the position of the shoe with respect to lateral swinging movement about

the axis of the pin 124, the machine herein shown is provided with a pair of side gages 126 arranged to engage the shoe at the opposite sides of the toe respectively when the operator presents it as above described. These side gages are supported by the slides 34 which carry the opposite side grippers 4, and, accordingly, they are adjusted for shoes of different widths by the means herein previously described for adjusting the side grippers. Each of the gages comprises an arm 128 a portion of which extends inwardly and downwardly toward the shoe and has on its inner end a facing of leather 130 or other suitable material for engagement with the upper. A substantially horizontal portion of the arm extends into a socket 132 formed in a holder 134, the arrangement being such that the arm may be preliminarily adjusted in directions widthwise of the shoe relatively to the holder. It is held in adjusted position by a screw 136 threaded in the holder and engaging a flat face on the arm. Each holder 134 is supported in a recess provided in a substantially U-shaped carrier 138 which has a laterally extending flange 140 (Figs. 1 and 5) secured in fixed relation to the corresponding cylinder 28 and slide 34 by the previously mentioned screw 30 and dowel pin 32. The holder is pivotally mounted at its outer end for swinging movements relatively to the carrier 138 in directions heightwise of the shoe about a pin 142. A screw 144 threaded in the holder 134 determines by engagement of its lower end with the carrier 138 the normal position of the holder with respect to movement about the pin 142, this screw being adjustable to vary the position heightwise of the shoe of the inner end of the gage arm 128. A nut 146 on the screw serves to lock it in adjusted position. To assist in maintaining the holder 134 in the position determined by the screw there is slidably mounted in the carrier 138 a pin 148 controlled by a spring 150 and engaging a downwardly extending portion 152 of the holder. It will be evident that the side gages 126 are in the paths of the wipers 8 when the latter are moved upwardly as hereinbefore described, and, accordingly, the springs 150 permit the gages and their holders 134 to be swung upwardly by the wipers about the pins 142, as illustrated in Fig. 4. It will be understood that by this time in the operation of the machine the shoe will have been clamped against the sole rest member 102 by the toe rest 12 and the instep support 14, so that the gages are no longer needed to position the shoe, and it will be further understood that the gages will have been moved short distances outwardly from the shoe by the movements of the slides 34 to operate the side grippers 4 prior to the upward movements of the wipers.

To assist in holding the shoe against lengthwise displacement from the position determined as above described, there is provided a heel-end support for the shoe, comprising a heel rest 154 (Figs. 5 and 6) which, for purposes of the present invention, is of different construction from that shown in Letters Patent No. 2,324,509 and is differently controlled. This heel rest is supported by a carrier 156, a portion only of which is herein shown, this carrier corresponding to the carrier 640 of the above-mentioned Letters Patent. From the disclosure of said Letters Patent it will be understood that the carrier 156 is mounted for swinging movement about an axis extending widthwise of the shoe to carry the heel rest lengthwise of the shoe into engagement there-

with. Adjustable upwardly or downwardly in the carrier is a rod 158 which is held in adjusted position by a spring-pressed pin 160 arranged to enter any one of a series of holes 162 in the rod. Secured on a reduced upper end of this rod, in the construction herein shown, is a downwardly extending sleeve portion 164 of a bracket 166 which is elongated widthwise of the shoe as shown in Fig. 6. The top face of this bracket serves as a support for a heel rest holder 168 provided with a pair of slots 170 through which extend headed studs 172 secured to the opposite ends of the bracket 166. Mounted on these studs within the slots are rolls 174 which facilitate movements of the holder 168 in directions widthwise of shoes in the machine. The holder is further held in place on the bracket by washers 176 mounted under the heads of the studs 172. Formed on the holder 168 are two rearwardly extending curved arms 178 provided with pins 180 on which are pivotally mounted the opposite ends of a chain 182 which is part of the heel rest 154 and serves as a backing for a flexible shoe-engaging band 184 of leather or other suitable material, the ends of this band being secured to the arms 178 by screws 186. To assist in supporting the chain, its middle link has a finger 188 extending therefrom into a slot 190 in the holder 168 and resting on the top of the bracket 166, the slot 190 being wider than the finger 188 to facilitate conformity of the heel rest to the contour of the heel-end face of the shoe.

As shown in Fig. 6, the heel rest 154 has a permanently concave contour widthwise of the shoe on the side toward the shoe and engages the heel-end face of the upper over a substantial area widthwise of the shoe to guard against any tendency to mark the upper by pressure unduly localized thereon. In view, however, of the fact that the arms 178 are in fixed relation to each other and hold the ends of the heel rest at all times farther apart than the width of the heel end of any shoe in the machine, the heel rest presses only on the heel-end face of the shoe and serves as an especially effective support for the shoe against lengthwise displacement. It will be evident that in order to avoid any tendency for such a heel rest to displace the heel end of a shoe laterally it should be properly centralized relatively to the shoe widthwise thereof, and it is for this purpose that the holder 168 is mounted for movements in directions widthwise of the shoe as above described, so that the heel rest may assume the proper positions relatively to right and left shoes the heel ends of which occupy somewhat different positions respectively widthwise of the machine. Since the heel rest would not readily adjust itself in proper relation to a shoe upon contact therewith if initially offset widthwise of the shoe, by reason of the friction between the band 184 and the upper, mechanism is further provided for properly centralizing it relatively to each shoe by movement of its holder 168. This mechanism comprises a pair of levers 192 pivotally mounted on pins 194 on the holder 168 and having curved arms 196 arranged to extend lengthwise of the shoe and to engage the opposite sides of its heel end below the heel rest 154. Light springs 198 connected to the previously mentioned pins 180 and to other arms 200 of these levers tend to swing the arms 196 inwardly toward each other and maintain them initially in positions determined by engagement of the arms 200 with pins

202 on the holder 168. Preferably the arms 196 are thus positioned near enough together to be wedged somewhat apart by any shoe on which the machine operates. It will, accordingly, be evident that as the heel rest is carried toward the shoe lengthwise thereof by the movement of the carrier 156, one or the other of the arms 196 will, upon engagement of the shoe therewith, cause the holder 168 to move in the proper direction to centralize the heel rest 154 relatively to the heel end of the shoe prior to its engagement with the shoe. In order to position the heel rest approximately in the proper relation to the shoe initially and thus to minimize the amount of movement of the holder 168 which results from engagement of the shoe with one or the other of the arms 196, there are provided two oppositely acting tension springs 204 each connected at one end to a pin 206 on the front of the holder 168 and at its other end to an arm 208 pivotally mounted on a stud 210 on the sleeve 164. The two springs 204 thus tend to centralize the holder 168 relatively to the arm 208, and this arm may be swung in opposite directions to cause the holder and the heel rest 154 to assume approximately the correct positions for right and left shoes respectively. Mounted on the arm 208 is a pin 212 having a pointed end arranged to enter any one of three recesses 214 in the front of the bracket 166 to hold the arm in different adjusted positions. The arm is resiliently flexible to permit it to be sprung forwardly to withdraw the pin from any one of the recesses, and has thereon a knob 216 for use in moving it. It will be understood that when the machine is to operate on right shoes the arm will ordinarily be shifted to the position determined by one of the extreme recesses 214 of the series, and that when it is to operate on left shoes it will be shifted to the position determined by the other extreme recess. Under some conditions, moreover, satisfactory results may be obtained with the arm positioned as determined by the middle recess of the series.

Having described the invention, what I claim as new and desire to secure by Letters Patent of the United States is:

1. In a shoe machine, the combination with means for operating on a shoe including an insole mounted on a last, of means for positioning the shoe bodily both lengthwise and laterally in proper relation to said operating means by engagement with the insole alone in a single hole previously formed therein, and additional means comprising side gages for determining the position of the shoe with respect to lateral swinging movement.

2. In a shoe machine, the combination with means for operating on a shoe including an insole mounted on a last, of means for positioning the shoe bodily both lengthwise and laterally in proper relation to said operating means by engagement with the insole alone in a single round hole previously formed in its forepart, and means arranged to engage the forepart of the shoe laterally to determine its position with respect to lateral swinging movement about the axis of said hole in the insole.

3. In a shoe machine, the combination with means for operating on a shoe including an insole mounted on a last, of a single pointed member arranged to engage the insole in a hole previously formed in its forepart and extending only part way through it to position the shoe bodily both lengthwise and laterally in proper relation to said operating means, and side gages located nearer

the end of the toe than said pointed member for determining the position of the shoe with respect to lateral swinging movement.

4. In a shoe machine, the combination with means for operating on a shoe including an insole mounted on a last, of a sole rest arranged to engage the bottom face of the forepart of the insole and having a single projection arranged to extend into a hole previously formed in the insole substantially midway between its opposite side edges to position the shoe bodily both lengthwise and laterally in proper relation to said operating means by engagement with the insole only, and members arranged to engage the shoe at the opposite sides of the forepart to determine its position with respect to lateral swinging movement.

5. In a shoe machine, the combination with means for operating on a shoe including an insole mounted on a last, of a sole rest arranged to engage the bottom face of the forepart of the insole to position the shoe heightwise and with respect to lengthwise or lateral tipping movement, said sole rest being adjustable as a whole about an axis extending widthwise of the shoe and having thereon a single projection arranged to extend into a hole previously formed in the insole substantially midway between its opposite side edges to position the shoe bodily both lengthwise and laterally.

6. In a shoe machine, the combination with wipers for wiping the marginal portion of an upper about the toe end of a last inwardly over an insole on the last, said wipers being movable heightwise of the shoe opposite the end and the sides of the toe prior to thus wiping the upper inwardly over the insole, of means for positioning the shoe bodily both lengthwise and laterally in proper relation to said wipers by engagement with the insole in a single hole previously formed in its forepart, and members arranged to engage the shoe at the opposite sides of the forepart to determine its position with respect to lateral swinging movement, said members being displaceable by the movement of the wipers heightwise of the shoe.

7. In a shoe machine, the combination with wipers for wiping the marginal portion of an upper about the toe end of a last inwardly over an insole on the last, said wipers being movable heightwise of the shoe opposite the end and the sides of the toe prior to thus wiping the upper inwardly over the insole, of means for positioning the shoe bodily both lengthwise and laterally in proper relation to said wipers by engagement with the insole in a single hole previously formed in its forepart, and members arranged to engage the shoe at the opposite sides of the forepart to determine its position with respect to lateral swinging movement, said members being supported for swinging movements heightwise of the shoe after the positioning of the shoe and being thus movable by engagement of the wipers therewith.

8. In a shoe machine, the combination with wipers for wiping the marginal portion of an upper about the toe end of a last inwardly over an insole on the last, said wipers being movable heightwise of the shoe opposite the end and the sides of the toe prior to thus wiping the upper inwardly over the insole, and grippers arranged to grip and pull the upper at the sides of the toe and adjustable widthwise of the shoe, of means for positioning the shoe bodily both lengthwise and laterally in proper relation to said wipers and grippers by engagement with the in-

sole in a single hole previously formed in its forepart, and members arranged to engage the shoe at the opposite sides of the forepart to determine its position with respect to lateral swinging movement, said members being supported for adjustment with the grippers and being displaceable by the movement of the wipers heightwise of the shoe.

9. In a shoe machine, the combination with wipers for wiping the marginal portion of an upper about the toe end of a last inwardly over an insole on the last, said wipers being movable heightwise of the shoe opposite the end and the sides of the toe prior to thus wiping the upper inwardly over the insole, of side gages supported independently of said wipers and arranged to engage the shoe at the opposite sides of the toe respectively for positioning the shoe relatively to the wipers, said gages being displaceable heightwise of the shoe by the movement of the wipers after the positioning of the shoe.

10. In a shoe machine, the combination with wipers for wiping the marginal portion of an upper about the toe end of a last inwardly over an insole on the last, said wipers being movable heightwise of the shoe opposite the end and the sides of the toe prior to thus wiping the upper inwardly over the insole, and grippers arranged to grip the upper at the sides of the toe and movable to pull the upper, of side gages arranged to engage the shoe at the opposite sides of the toe respectively for positioning the shoe relatively to the wipers, said gages being supported for movements with the grippers and being displaceable by the movement of the wipers heightwise of the shoe.

11. In a shoe machine, the combination with wipers for wiping an upper about the toe end of a last into lasted position, and grippers arranged to grip the upper at the sides of the toe and movable to pull the upper, of side gages arranged to engage the shoe at the opposite sides of the toe respectively for positioning the shoe relatively to the wipers, said gages being supported for movements with the grippers.

12. In a shoe machine, the combination with wipers for wiping an upper about the toe end of a last into lasted position, and grippers arranged to grip the upper at the sides of the toe and movable in directions widthwise of the shoe to pull the upper, of side gages arranged to engage the shoe at the opposite sides of the toe respectively for positioning the shoe relatively to the wipers, said gages being supported for movements widthwise of the shoe with the grippers after the positioning of the shoe.

13. In a shoe machine, grippers arranged to grip the marginal portion of an upper on a last at the opposite sides of the toe respectively for pulling the upper, said grippers being adjustable in directions widthwise of the shoe, and side gages arranged to engage the upper at the opposite sides of the toe respectively for positioning the shoe, said gages being supported for adjustment with the grippers.

14. In a shoe machine, the combination with means for operating on shoes, of a heel rest arranged to engage the heel-end face of each shoe to support the shoe against lengthwise displacement, said heel rest being mounted for movements in directions widthwise of the shoes, and controlling means thus movable with the heel rest and arranged to engage each shoe to position the heel rest in proper relation to the shoe widthwise thereof.

15. In a shoe machine, the combination with means for operating on shoes, of a heel rest arranged to engage the heel-end face of each shoe to support the shoe against lengthwise displacement, said heel rest being mounted for movements in directions widthwise of the shoes, and members thus movable with the heel rest and arranged respectively to engage the opposite sides of the heel end of each shoe to position the heel rest in proper relation to the shoe widthwise thereof.

16. In a shoe machine, the combination with means for operating on shoes, of a heel rest arranged to engage the heel-end face of each shoe to support the shoe against lengthwise displacement, a holder supporting said heel rest and mounted to move with it in directions widthwise of the shoes, and a pair of curved arms carried by said holder and arranged to extend lengthwise of the shoes for engagement respectively with the opposite sides of the heel end of each shoe to position the holder and the heel rest in proper relation to the shoe widthwise thereof.

17. In a shoe machine, the combination with means for operating on shoes, of a heel rest arranged to engage the heel-end face of each shoe to support the shoe against lengthwise displacement, a holder supporting said heel rest and mounted to move with it in directions widthwise of the shoes, a pair of arms carried by said holder and arranged respectively to engage the opposite sides of the heel end of each shoe to position the holder and the heel rest in proper relation to the shoe widthwise thereof, and spring means arranged to control said arms and against the resistance of which they are movable away from each other by engagement of a shoe therewith.

18. In a shoe machine, the combination with means for operating on shoes, of a heel rest arranged to engage the heel-end face of each shoe to support the shoe against lengthwise displacement, said heel rest being mounted for movements in directions widthwise of the shoes, means thus movable with the heel rest and arranged to engage each shoe to position the heel rest in proper relation to the shoe widthwise thereof, and spring means arranged to control said heel rest and against the resistance of which it is thus movable.

19. In a shoe machine, the combination with means for operating on shoes, of a heel rest arranged to engage the heel-end face of each shoe to support the shoe against lengthwise displacement, said heel rest being mounted for movements in directions widthwise of the shoes, means thus movable with the heel rest and arranged to engage each shoe to position the heel rest in proper relation to the shoe widthwise thereof, and a pair of oppositely acting springs arranged to maintain said heel rest initially in a predetermined position widthwise of the shoe while permitting it thus to be moved to a position determined by the shoe.

20. In a shoe machine, the combination with means for operating on shoes, of a heel rest arranged to engage the heel-end face of each shoe to support the shoe against lengthwise displacement, said heel rest being mounted for movements in directions widthwise of the shoes, means thus movable with the heel rest and arranged to engage each shoe to position the heel rest in proper relation to the shoe widthwise thereof, a pair of springs tending respectively to move said heel rest in opposite directions and arranged to maintain it initially in a predetermined position widthwise

of the shoe, and a member arranged to control both said springs and movable to adjust the heel rest through the springs to different initial positions for operating on right and left shoes respectively.

21. In a shoe machine, the combination with means for operating on shoes, of a heel rest movable toward each shoe lengthwise thereof into engagement with the heel end of the shoe to support the shoe against lengthwise displacement, said heel rest being mounted for movements in directions widthwise of the shoes, and controlling means arranged to engage the heel end of each shoe to shift the heel rest automatically into proper relation to the shoe widthwise thereof as it is moved toward the shoe.

22. In a shoe machine, the combination with means for operating on shoes, of a heel rest movable toward each shoe lengthwise thereof into engagement with the heel-end face of the shoe to support the shoe against lengthwise displacement, said heel rest having a concave shoe-engaging face and being mounted for movements in directions widthwise of the shoes, and members arranged respectively to engage the opposite sides of the heel ends of the shoes for shifting the heel rest automatically in one direction or the other widthwise of each shoe into proper relation thereto as it is moved toward the shoe.

23. In a shoe machine, the combination with means for operating on shoes, of a heel rest movable toward each shoe lengthwise thereof into engagement with the heel end of the shoe to support the shoe against lengthwise displacement, a holder supporting said heel rest and mounted to move with it in directions widthwise of the shoes, and a pair of arms on said holder arranged respectively to engage the opposite sides of the heel ends of the shoes to shift the holder and the heel rest automatically in one direction or the other widthwise of each shoe into proper relation thereto as the heel rest is moved toward the shoe.

24. In a shoe machine, the combination with means for operating on shoes, of a heel rest movable toward each shoe lengthwise thereof into engagement with the heel end of the shoe to support the shoe against lengthwise displacement, said heel rest being mounted for movements in opposite directions widthwise of the shoes, spring means arranged to maintain said heel rest initially in a predetermined position with respect to such opposite movements, and members arranged respectively to engage the opposite sides of the heel ends of the shoes for shifting the heel rest automatically in one direction or the other against the resistance of said spring means into proper relation to each shoe as it is moved toward the shoe.

25. In a shoe machine, the combination with means for operating on shoes, of a flexible heel rest arranged to extend widthwise of each shoe beyond the sides thereof to support the shoe against lengthwise displacement by engagement with the heel end of the upper, supporting means connected to the opposite ends of said heel rest and arranged to hold said ends in fixed relation to each other far enough apart to confine the heel rest to engagement with the heel-end face of the upper, and additional means for engaging the sides of the heel end of each shoe further to determine the positional relation of the shoe and the heel rest to each other.

26. In a shoe machine, the combination with means for operating on shoes, of a flexible heel rest arranged to extend widthwise of each shoe

to support the shoe against lengthwise displacement by engagement with the heel end of the upper, said heel rest comprising a flexible shoe-engaging band and a chain arranged to serve as a backing for said band, supporting members connected to the ends of said chain and arranged to hold said ends in fixed relation to each other far

enough apart to confine the heel rest to engagement with the heel-end face of the upper, and means for engaging the sides of the heel end of each shoe further to determine the positional relation of the shoe and the heel rest to each other.

BERNHARDT JORGENSEN.
